(57) CLAIM

The ornamental design for a cupboard as shown and described.

DESCRIPTION

FIG. 1 is a perspective view of a cupboard showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area 9 shown in FIG. 3; and, FIG. 10 is an enlarged view of area 10 shown in FIG. 3.

The dashed broken lines depict portions of the cupboard that form no part of the claimed design. The dot-dash lines define the perimeters of enlarged areas shown in FIGS. 9 and 10 and form no part of the claimed design.

1 Claim, 10 Drawing Sheets
